UNITED STATES PATENT OFFICE.

HENRY L. BANTA AND CHARLES W. BANTA, OF CANON CITY, COLORADO.

CAR-COUPLING.

SPECIFICATION forming part of Letters Patent No. 392,303, dated November 6, 1888.

Application filed May 24, 1888. Serial No. 275,977. (No model.)

To all whom it may concern:

Be it known that we, HENRY L. BANTA and CHARLES W. BANTA, of Canon City, in the county of Fremont and State of Colorado, have 5 invented certain new and useful Improvements in Car-Couplings; and we do hereby declare the following to be a full, clear, and exact specification of the same.

This invention has in view to provide an 10 improved car-coupling which is simple and readily operated without requiring the operator to pass in between the cars, which would expose him to the danger of being crushed thereby, and which is adapted to guide the 15 coupling-link into the approaching draw-head, while the retention of the pin-adjusting mechanism or rack, either when the pin is in a lowered or coupled position or in an elevated or uncoupled position, is effected automatically; 20 and to these ends the nature of the invention consists of the peculiar construction and arrangement of the coupling-pin-adjusting mechanism and of the link-adjusting contrivance, all substantially as hereinafter more fully set forth, and pointed out in the claims.

25 In the accompanying drawings, Figure 1 is a front elevation of our improved car-coupling with the coupling-pin in its elevated or uncoupled position. Fig. 2 is a sectional elevation thereof with the coupling-pin in its lowered or coupled position; and Fig. 3 is a plan view thereof. Fig. 4 is an enlarged detail view of the coupling-pin-carrying arm of the 30 adjusting-rack. Fig. 5 is a similar view of the link-adjuster applied to the under side of the draw-head.

In the embodiment of our invention we employ an upright rack, A, which slides in keepers or brackets a a , applied to the end of the 35 car at suitable points thereon. The lower end of the rack is provided with a horizontal arm, a' , having its forward end tapered, as at a'' , at the inner end of which taper is a shoulder, a''' , to permit of the suspension therefrom and the retention in a vertical position of the coupling-pin B. Applied to the arm a' of the rack A is a spring or clasp, b, the forward or outer end of which is convexed or bowed downward, with its convexity resting upon the upper surface 40 of the tapered forward end of the arm a' , the

extreme forward ends of the arm and spring or clasp standing apart to permit of the ready insertion between them in passing or slipping the coupling-pin to its place upon said arm. With the rack A gears a pinion, C, upon a 55 horizontal shaft, c, suitably journaled at the end of the car, and provided with cranks or handles $c' c'$ —one at each end—for its operation.

D is a spring-pawl secured at its outer or one end to the end of the car and having its 60 opposite end adapted to enter or engage with a notch or recess, d, in the outer or front side of the rack A, when the latter is adjusted, so as to hold the coupling-pin in its elevated or uncoupled position. The spring-pawl D, when 65 the rack A is moved downward, glides out of the notch or recess d of the rack, and bearing against the latter, after leaving said recess or notch, will spring over and bear upon the upper end of said rack, thus effecting the holding 70 of the coupling-pin in its lowered or coupled position.

The upper end of the rack A is beveled or inclined from the front side of the rack, as at 75 e, to permit of the ready passage of the free end of the pawl D thereon and therefrom, according to the direction of movement imparted to the rack.

E is the link-adjuster or contrivance which is applied to the under side of the draw-head 80 f, near one side thereof; and it consists of a spring-metal plate having its forward or free end convexed or bowed upward beyond the outer end of the draw-head f, with its convexity standing about in the same plane with the 85 bottom surface of the draw-head chamber, to effect the ready guidance thereinto of the link of the meeting draw-head. As the meeting draw-head comes in contact with the projecting convexed portion of the link-adjuster or 90 contrivance E, the latter will yield downwardly and pass under said meeting draw-head, and thus permit of the draw-heads having the required contiguity of approach, and the said projecting portion being taken out of the way, 95 preventing the breaking of the same.

This car-coupling is simple, and permits of operation without the operator or train-man going in between the cars to effect the coupling of the cars or the uncoupling thereof; be- 100

sides, the retention of the coupling-pin-adjusting mechanism, either in a lowered or elevated position, is effected automatically to prevent the accidental displacement of the coupling-
5 pin either in its coupled or uncoupled position.

Having thus fully described our invention, what we claim, and desire to secure by Letters Patent, is—

1. The car-coupling having the sliding rack 10 provided with an arm connecting with the coupling-pin, and means for operating said rack, substantially as set forth.

2. The car-coupling having the sliding rack connected with the coupling-pin, and having a 15 beveled or inclined upper end and a notch a short distance below said end, in combination with a spring - pawl engaging automatically with said beveled upper end and notch of the sliding rack, substantially as set forth.

20 3. The car coupling having the sliding rack provided with an arm having a tapered and shouldered forward end, a spring or clasp applied to said arm and having its downwardly-bowed or convexed end resting upon the tapered end of the rack-arm to effect the suspension therefrom of the coupling - pin, and means for operating said rack, substantially as set forth.

4. The car-coupling having the sliding rack provided with a beveled or inclined upper end 30 and a notch or recess upon its front side a short distance below said end, and with a horizontal arm at its lower end having a tapered and shouldered forward end, said arm having a spring or clasp applied to its upper side, 35 which clasp or spring is convexed or bowed at its outer end, with its convexity resting upon the tapered end of the arm, in combination with the pinion secured upon a handled or cranked shaft and gearing with said rack, and 40 the spring-pawl engaging with the notch and the beveled or inclined upper end of the rack, substantially as set forth.

5. The car-coupling having the link-adjuster applied to the under side of the draw-head, 45 and consisting of a spring-metal plate having a convexed or bowed forward end standing beyond the outer end of the draw-head, substantially as set forth.
